George D. Young

UNITED STATES PATENT OFFICE.

GEORGE D. YOUNG, OF PLYMOUTH, MASSACHUSETTS.

BELT OR BAND FASTENING.

Specification of Letters Patent No. 14,175, dated January 29, 1856.

To all whom it may concern:

Be it known that I, GEORGE D. YOUNG, of Plymouth, in the county of Plymouth and State of Massachusetts, have invented 5 certain new and useful Improvements in Clasps for Uniting Belts or Banding, and that the following description, taken in connection with the accompanying drawings, hereinafter referred to, forms a full and 10 exact specification of the same, wherein I have set forth the nature and principles of my said improvements by which my invention may be distinguished from others of a similar class, together with such parts as I 15 claim and desire to have secured to me by Letters Patent.

The figures of the accompanying plate of drawings represent my improvements.

Figure 1, is a plan or top view of my im- 20 proved clasp. Fig. 2 is a longitudinal vertical section of the same taken in the plane of the line A B, Fig. 1. Fig. 3 is a trans- 25 verse vertical section taken in the plane of the line C D, Fig. 1.

The usual methods heretofore devised for 30 uniting the ends of belts, or bands, used in giving motion to machinery, by means of lacings, or plates of metal screwed together and gripping the belt between them, are ob- 35 jectionable for many reasons, the latter de- 40 vice, which is the more recent one, being found inconvenient in use on account of the difficulty of inserting or removing the screws, without taking the belt off from its 45 drum or pulleys, when the same requires shortening or readjustment.

My improved clasp is so constructed as to allow of its being taken off the belt, or re- 50 placed upon the same, whenever it is desir- 55 able to do so, with the greatest ease and facility.

It consists of a plate of metal provided 60 with short vertical studs, that project up through the ends of the belt, and is held in 65 position so as to rigidly grip the ends of the belt, by a top plate having suitable

holes that fit over the vertical studs of the lower plate, and a turning button attached to the top plate, which engages with notches formed in two of the vertical studs, and thereby holds the two plates rigidly upon the belt. 50

a, a, in the drawings represent the two ends of the belt to be united.

b b is a bottom plate, formed of metal, 55 provided with short vertical studs *c, c, c*, &c. The studs are inserted through each end *a, a* of the belt, and also through proper holes formed in a top plate *d d*, the studs *c, c* projecting slightly above the face of 60 the top plate.

e is a button turning on a pivot *f* in the top plate *d d*. By turning this button, it can be engaged with notches formed in the center studs *c, c*, as shown in the drawings, 65 thereby rigidly gripping the ends of the belt between the two plates *b b* and *d d*, or disengaged from the said notches, whereby the top plate can be readily taken off the studs *c, c*, and the lower plate *b b*, removed 70 from the belt, as will readily be understood without further explanation. The convenience of this arrangement will readily be apparent, as the two ends of a belt can be united with the greatest facility, and without the use of screws, while by simply turning the button *e*, the clasp can be at once removed from the belt whenever desirable. 75

Having thus described my improvements I shall state my claim as follows: 80

What I claim as my invention and desire to have secured to me by Letters Patent is—

A clasp for uniting the ends of a belt or band, consisting of the button plate with its vertical studs, the top plate fitting over the 85 said studs, and the turning button, or its equivalent, all operating together to rigidly grip the belt or band, as described.

GEORGE D. YOUNG.
